TYPEWRITING AND LIKE MACHINE

Russell G. Thompson, Elmira, N. Y., assignor to
Remington Rand Inc., Buffalo, N. Y., a corpora-
tion of Delaware

Application November 17, 1939, Serial No. 304,988

4 Claims. (Cl. 197—169)

My invention relates to typewriting and like machines, and more particularly to improved ribbon feeding mechanism for such machines.

The main object of my invention, generally stated, is to provide improved means of the character specified which is simple, reliable and highly effective in operation.

A further object of my invention is to provide an improved means for preventing unnecessary and undesirable feed of the ribbon in a typewriting machine.

A still further object of my invention is to provide improved means for preventing feed of the ribbon during free movements of the carriage under control of either the tabulator or carriage release mechanism in a typewriting machine wherein the ribbon feeding mechanism is driven by movement of the carriage in a letter space direction.

To the above and other ends which will herein-after appear, my invention consists in the features of construction, arrangements of parts and combinations of devices set forth in the following description and particularly pointed out in the appended claims.

In the accompanying drawings, wherein like reference characters indicate corresponding parts in the different views:

Fig. 1 is a transverse, vertical, sectional view taken through the central portion of a typewriting machine and illustrating only a sufficient number of parts thereof to show my invention in its embodiment therein.

Fig. 2 is an enlarged, fragmentary, fore and aft, vertical sectional view of the same taken on line 2—2 of Fig. 1 and viewed in the direction of the arrows at said line.

Fig. 3 is an enlarged, fragmentary, fore and aft, vertical sectional view taken on line 3—3 of Fig. 1 and viewed in the direction of the arrows at said line.

Fig. 4 is an enlarged, fragmentary, horizontal sectional view taken on line 4—4 of Fig. 1 and viewed in the direction of the arrows at said line.

Fig. 5 is a view similar to Fig. 4 but with certain parts shown in a different operated position.

Fig. 6 is an enlarged, fragmentary, perspective view showing various details of the construction shown in the above mentioned views.

Fig. 7 is an enlarged, fragmentary perspective view showing a portion of the escapement mechanism.

I have shown my invention embodied in the present instance in a Remington Model No. 17 typewriting machine, in which the features of

the invention may be readily incorporated with but few changes in the existing structure. However, it is to be understood that my invention is not restricted to embodiment in such machines but may be employed in various other types of typewriting and like machines wherever found available.

The drawings show only so much of the construction of the Remington Model No. 17 machine as is necessary to arrive at an understanding of the present invention in its embodiment therein.

In this machine, many of the parts, including the type actions, key levers and various other related mechanisms are mounted in a removable chassis formed by side plates 10 which are rigidly connected by cross members which are not shown in the drawings. This chassis is removably mounted within an exterior frame or casting which includes a U-shaped member having side portions 12, which, as may be seen in Fig. 1, extend along the side plates 10 of the chassis in spaced relation thereto, and the rearward end portions of these side portions 12 are rigidly interconnected by suitable cross members, such as the rear cross member 13 shown in part in Fig. 1. The detailed construction of the chassis and the exterior frame together with the means for removably holding the chassis securely within the exterior frame are fully disclosed within my companion application filed July 26, 1940, Serial No. 347,677.

The carriage in the present machine is removably mounted on the rear upper portion of the side members 12 of the exterior frame. Thus, as may be seen in Figs. 1 and 2, a stationary carriage guide member 15 is removably mounted on the side members 12 of the exterior frame by means which have not been shown, and a traveling carriage frame 16 is mounted by crossed anti-friction rollers 17 on the supporting member 15 for movement transversely of the machine in the usual manner. The traveling carriage frame member 16 is provided with carriage end plates 18, and a platen 20 is mounted to turn therein in the usual manner.

The carriage thus mounted for movement transversely of the machine is impelled in a letter spacing direction from right to left by a spring drum 24. This drum is mounted to turn about the axis of a shaft 25 carried by the rear cross member 13 of the exterior frame and supported at its front end by a bracket 27 secured at 28 to the rear cross member 13. The spring drum 24 includes the usual spiral internal spring

(not shown) which exerts a force tending to turn the drum 24 in a counter-clockwise direction as viewed in Fig. 1, and the drum is operatively connected to the carriage by a flexible tape 30 which extends around the periphery of the drum. Thus, one end of the tape 30 is anchored to the spring drum while the other end is provided with a connecting piece 31 which is detachably connected to an arm 32 secured to the right hand carriage end plate 18. The spring drum 24 is thus turned in a counter-clockwise direction to move the carriage in a letter spacing direction from right to left of the machine, and a return movement of the carriage accordingly effects a reverse or clockwise turning movement of the drum through the tape 30.

The movement of the carriage in a letter spacing direction from right to left is controlled by an escapement mechanism which as shown in Figs. 1 and 2 includes a feed rack 35 rigidly secured to the carriage end plates 18 to be constantly in mesh with a feed pinion 38. This feed pinion is mounted to turn on a bearing screw 39 carried by a bracket 41 which is secured at 42 to the rear cross member 13 of the exterior frame. A tooth escapement wheel 45 is formed integral with the feed pinion 38, and a feed dog 47 normally coacts with the escapement wheel 45 to prevent rotation thereof under the force of the carriage spring drum.

Referring to Figs. 1, 2 and 7, it will be seen that the feed dog 47 is pivotally mounted at 48 on the upper end of an arm 49 which is in turn pivotally mounted at 50 on a dog rocker 51. A contractile spring 52 acting on a depending arm of the dog 47 resiliently holds the free end of the dog in its upper position where it engages and holds one of the teeth of the escapement wheel. The dog rocker 51 is pivotally mounted at 53 (see Fig. 1) between extensions 54 of the bracket 41, and the usual connections (not shown) are provided between the dog rocker 51 and the universal bar on the type bar segment as well as with the space key mechanism whereby the dog rocker is actuated upon each operation of a printing key or the space key. Actuation of the dog rocker 51 moves the normally engaged dog 47 transversely of the escapement wheel to a position releasing the escapement wheel for movement under the force of the spring drum so that an oncoming tooth of the escapement wheel engages a holding dog formed by a portion 51a (see Fig. 7) of the dog rocker 51, and when the dog rocker returns to its illustrated normal position this tooth of the escapement wheel engages the pivoted dog 47 to arrest movement of the carriage in the usual manner.

The present machine also includes mechanism mounted on the carriage which is manually operable to free the carriage from control of its escapement mechanism and afford free movement of the carriage in a letter space direction. This manual release mechanism includes release levers 60, as shown in Figs. 1 and 2, one mounted at each end of the carriage on respective end portions of a rock shaft 61 which is supported in bearing openings in the carriage end plates 18. A bail 63 is secured to the rock shaft 61 and this bail is formed in the present instance by a sheet metal strip or vane extending throughout the central portion of the rock shaft 61 and suitably attached thereto, as by welding. A coil spring 64 is provided around the right hand end portion of the rock shaft 61 as shown in Fig. 1 and coacts between the bail 63 and the

right hand carriage end plate 18 to resiliently hold the bail, rock shaft and carriage release levers in their illustrated normal position.

The lower edge of the bail 63 coacts with a roller 68, which as shown in Fig. 2, is pivotally mounted at 69 at the upper end of an arm 70. Referring to Figs. 1, 2 and 6, it may be seen that the arm 70 is provided with lateral extending portions forming a yoke 71 by which it is mounted to turn on a shaft 72. The shaft 72 is carried by a bracket 73 secured at 74 (see Fig. 1) to the rear cross member 13 of the exterior frame. The arm 70 is resiliently held in its normal position where the roller 68 is disposed in cooperative relation with the bail 63 by a contractile spring 76. Said spring extends between a depending portion 77 of the yoke 71 and a rearwardly extending portion 78 (see Fig. 6) of a yoke 80 which is also mounted to turn on the shaft 72 for purposes which will later be described. The yoke 80 is in turn resiliently held in its normal position by a contractile spring 82 extending between a pin 83 on the yoke 80 and a rod 84 carried by the bracket 73, as shown in Figs. 1 and 6.

Referring to Figs. 2 and 6, it will be seen that the arm 70 is provided with a rearwardly extending portion 83 which normally overlies the central portion of the pivoted feed dog 47. Thus, a rocking movement of the arm 70 around the shaft 72 causes a downward pivotal movement of the dog 47 against the force of the spring 52 to a position where the free end of the dog is out of the path of the teeth of the escapement wheel 45. It will now be clear that manual operation of either of the carriage release lever 60 will move the bail 63 rearward against the force of the spring 64, thereby engaging the roller 68 to move the arm 70 about the shaft 72 and release the carriage for free movement in a letter spacing direction. Inasmuch as the bail 63 is sufficiently long to coact with the roller 68 regardless of the position of the carriage, it will be clear that the present arrangement is operative to release the normally engaged escapement dog 47 with equal facility at any position of the carriage.

The usual tabulator mechanism provided in the present machine also includes means for releasing the carriage for movement in a letter spaced direction. This tabulator mechanism includes the usual tabulator key or keys at the keyboard of the machine and supported at the forward end of associated levers pivotally mounted intermediate of the machine, but the showing of these keys and levers has been omitted from the drawings. It is to be understood, however, that these tabulator keys and levers may be of the usual construction arranged so that each key lever affords a rearward movement of an associated link 90 shown in Fig. 2. Each of the links 90 is connected at its rearward end, at 91 to a companion bell crank 92 which is mounted to turn on a pivot rod 93 carried by a portion 94 of the chassis frame. The rearward portion of each of the cranks 92 is provided with an adjustable screw 95 which operatively connects it with the lower end of a companion tabulator stop plunger 96 which is arranged in an associated guide slot 96a (Figs. 2 and 6) in the lower portion of the bracket 73. There are two of these tabulator stop plungers 96 shown in Fig. 1, but it is to be understood that the machine may be equipped with only one or with more of these

plungers as may be required for the particular tabulating operations desired.

The upper end portion of each of the stop plungers 96 is guided by an associated slot in the edges of guide bars 93 secured to the rear cross member 13 of the exterior frame. Thus, each of the stop plungers 96 may be moved upward by a depression of the associated tabulator key to position the upper end of the plunger into the path of travel of a downwardly projected carriage carried column stop 100. These stops 100 may be of the usual construction arranged at letter space intervals on a stop bar 101 mounted on the carriage in the usual manner. The stop bar 101 is arranged to hold each of the stops 100 either in its normal ineffective position as shown in Fig. 2 or to allow one or more of the stops to be projected downward to a position where it may coact with any of the elevated stop plungers 96 mounted on the frame of the machine to arrest movement of the carriage in a letter space direction.

Referring more particularly to Figs. 2 and 6 it will be seen that each of the tabulator stop plungers 96 is provided with a forward extending portion 105 which is engaged by the lower edge of the yoke 80 under the force of the spring 82, and accordingly when any one of the stop plungers 96 is operated upward by a depression of the associated tabulator key, the yoke 80 is turned in a clockwise direction as viewed in Fig. 2 about the shaft 72. The right hand arm of the yoke 80 is provided with a downwardly extending lug portion 106 (see Figs. 2 and 6) which coacts with a downwardly extending lug 107 on the yoke 71. Thus, as the yoke 80 is rocked by depression of a tabulator key, the lug 106 engages and operates the lug 107 to rock the arm 70 about the shaft 72, thereby moving the extension 88 downward to release the holding dog 47 from the escapement wheel and free the carriage for movement in a letter space direction as previously pointed out. It will be noted in Figs. 2 and 6 that the extension 107 normally engages a lateral extension 110 at the right hand side of the bracket 73 and accordingly limits the return movement of the yoke 71 to normal position under the force of the spring 76.

The feeding mechanism for the inking ribbon in the present machine is driven by the turning movement of the spring drum 24, and is arranged so that the ribbon is fed intermittently past the printing point as the spring drum is turned in a counter-clockwise direction as shown in Fig. 1, to impel the carriage in its step by step movement from left to right of the machine for the spacing of written characters. Thus as will be seen in Figs. 1 and 3, a ring gear 115 is fixedly secured to the front face of the spring drum 24 in any suitable manner, such as by spot welding, and the ring gear 115 normally meshes with a smaller pinion gear 116. Said pinion gear is mounted to turn freely on the rear end portion of a shaft 117 which extends fore and aft of the machine in the space between the left hand chassis side plate 10 and the left hand side portion 12 of the exterior frame, as shown in Fig. 1.

The rear end portion of the shaft 117 is mounted to turn in a U-shaped bracket member 120 which is pivotally supported by a screw 121 on an inwardly extending portion 122 of the left hand side portion 12 of the exterior frame. The front end of the shaft 117 is supported by a bearing plate 124 which is secured at 125 to a

bracket member 126 which is in turn secured by means, not shown, to the side portion 12 of the exterior frame. The bracket member 120 is resiliently held in a position shown in Fig. 5 1, wherein the pinion gear 116 meshes properly with the ring gear 115, by a contractile spring 128 connecting the upper portion of the member 120 with a lug 129 on the bracket 27.

In order to insure proper meshed relation between the pinion gear 116 and the ring gear 115, an adjustable stop means is provided for limiting the movement of the bracket member 120 under the force of the spring 128. This adjustable stop means is provided in the present instance by a stop screw 132 threaded into a tapped opening in an extension 133 of the bracket 27 (see Fig. 1), and the end of this stop screw 132 engages an upstanding lug 134 on the U-shaped bearing member 120 to limit the inward movement thereof under the force of the spring 128.

A one-way driving connection is provided between the pinion gear 116 and the shaft 117 in order that the shaft will be turned only during the travel of the carriage in a letter space direction. Referring to Fig. 3, it will be seen that this driving connection is generally of the usual construction including a disc 136 having a hub portion secured at 137 to the shaft 117, which disc carries a pawl 138 pivoted thereon at 139. A spring 140 acts to resiliently hold the free end of the pawl 138 in cooperative relation with ratchet teeth 141 formed on the front end of the hub portion of the pinion gear 116, whereby turning movement of the gear 116 in one direction only is transmitted to the shaft 117. In order to prevent reverse rotation of the shaft 117 when the gear 116 is turned in the other direction, a second pawl 143 is pivoted at 144 on the bearing member 120, and a spring 145 resiliently holds the free end of this pawl 143 in cooperative relation with ratchet teeth 146 formed on the hub portion of the disc 136 which is secured to the shaft 117. Thus, it will be clear that this arrangement causes the shaft 117 to be driven by the pinion gear 116 when it is turned by the spring drum during the travel of the carriage in a letter spacing direction but allows the pinion gear to turn freely on the shaft 117 during the reverse rotation of the spring drum at which time a reverse rotation of the shaft 117 is prevented by the pawl 143 and ratchet teeth 146.

The front end of the shaft 117 is provided with a beveled pinion gear 150 secured thereto at 151 to mesh with a beveled gear wheel 152 mounted to turn freely on a headed pivot screw (not shown) carried by the upper end of the bracket 126 which is secured to the side portion 12 of the exterior frame, as previously pointed out. The parts of the ribbon driving mechanism thus far described are all mounted on and carried by the exterior frame of the machine while the ribbon itself and the remainder of the ribbon feeding mechanism is mounted on and carried by the removable chassis. Accordingly connecting means are provided between the gear wheel 152 and the ribbon feeding mechanism mounted on the removable chassis which permits the chassis to be readily removed from the exterior frame.

This connecting means is provided in the present instance by a pin 154 secured to the gear wheel 152 to extend inwardly therefrom, and this pin normally enters a bifurcation 155 in an arm 156 which is fixedly secured to the extreme left

hand end portion of a shiftable ribbon drive shaft 157. The shaft 157 extends transversely of the machine in axial alignment with the axis of the gear wheel 152, and is mounted on and carried by the removable chassis in bearing openings provided in each of the end plates 10. In this manner, the ribbon driving mechanism carried by the external frame is operatively connected to the shaft 157 through the pin 154 and bifurcated arm 156 when the chassis is in normal position, but the bifurcation 155 in the arm 156 permits the chassis to be lifted upward and forward out of the exterior frame and to be readily replaced therein.

The portion of the ribbon feeding mechanism mounted on the removable chassis and controlled by the shiftable drive shaft 157 is not modified by the devices of the present invention, and for a detailed disclosure of this mechanism, reference is made to my co-pending application filed September 29, 1939, Serial No. 297,135. However, this mechanism may be generally described as including a ribbon spool shaft at each side of the chassis, only the left hand spool shaft 160 being shown in the drawings, but it will be understood that the right hand spool shaft may be arranged in a substantially identical manner at the other side of the chassis. Each of the spool shafts 160 is mounted to turn in a companion bracket 161 secured to the associated side plate 10 of the chassis, and a ribbon spool 162 carrying an inking ribbon 163 is removably mounted on the upper end of each of the spool shafts.

The ribbon drive shaft 157 has a beveled gear 165 secured to the left hand portion thereof which may be moved into meshed relation with a beveled gear 166 secured to the lower end of the left hand ribbon spool shaft 160. It will be understood that a beveled gear similar to 165 is also provided at the right hand portion of the drive shaft 157 which may be moved into meshed relation with a beveled gear similar to 166 which is secured to the lower end of the right hand ribbon spool shaft. Thus, the shiftable ribbon drive shaft 157 is driven by the spring drum 24 during the intermittent letter spacing movements of the carriage, and the shaft 157 may be selectively positioned to drive either the right hand or the left hand ribbon spool shaft to accordingly feed the ribbon 163 in one direction or the other past the printing point in the usual manner.

Means are provided in accordance with the present invention for preventing unnecessary and undesirable feeding of the ribbon such as ordinarily occurs during free movements of the carriage in a letter spacing direction afforded by a depression of a carriage release key or an operation of the tabulator mechanism. This result is accomplished in the present instance by a very simple yet highly effective mechanism for moving the pinion gear 116 out of cooperative relation with the spring drum ring gear 115 whenever the normally engaged escapement dog 47 is moved downward out of the path of the teeth of the escapement wheel to afford a free movement of the carriage in a letter spacing direction.

The specific means, best shown in Figs. 1, 3 and 6 of the accompanying drawings, for obtaining this result includes an extension or arm 170 (see Fig. 6) secured at 171 to the arm 70 which is rocked by the carriage release mechanism or the tabulator mechanism to disengage the pivoted dog 47 from the teeth of the escapement wheel 45. An adjustable operating connection is provided at the free end of the arm 170 by a screw

170^a threaded in a tapped opening therein and locked in its adjusted position by a nut 172. The lower end of the screw 170^a is arranged to engage and operate the horizontal arm of a bell crank 5 173 which is pivotally mounted at 174 on an extension 175 of the stationary bracket 27. The depending arm of the bell crank 173 is pivotally connected at its lower end at 177 to a link 178, which link is bifurcated at its other end to straddle a reduced portion of a lug 180 extending inwardly from the central portion of the front arm of the U-shaped bracket 120, as shown in Figs. 1 and 3.

Referring to Fig. 4, it will be seen that the bearing openings in the U-shaped bracket 120 which receive the shaft 117 are elongated horizontally to permit a slight shift in the alignment of the shaft 117 with relation to the bracket 120. The opening in the bearing plate 124 which receives the other end of the shaft 117 is also slightly enlarged, and this mounting of the shaft 117 allows a pivotal movement of the U-shaped bracket 120 about the axis of the screw 121 to move the pinion 116 from its position shown in Fig. 4, wherein it is in meshed relation with the ring gear 115, to its position shown in Fig. 5 wheren the teeth of the pinion 116 are entirely free from the path of movement of the teeth of the ring gear 115. In other words, the elongated holes in the bracket 120 and bearing member 124 allow the rear end of the shaft 117 to be swung in an arc substantially about its bearing in the plate 124 by a pivotal movement of the bracket 120.

It will now be apparent that whenever the arm 70 is rocked about the shaft 72 to free the carriage from control of its escapement mechanism for movement in a letter space direction, the arm 110 will operate the bell crank 173 to rock the U-shaped bracket 120 about its pivot 121 through the link 178 thereby moving the pinion gear 116 out of meshed relation with the spring drum ring gear 115. Thus, whenever either the carriage release lever 60 or the tabulator mechanism is operated to afford a free movement of the carriage in a letter space direction, the ribbon feeding mechanism is rendered inoperative. In this manner, the ribbon is fed only during the intermittent letter spacing movements of the carriage for the spacing of written characters, and unwarranted and undesirable feed of the ribbon is prevented during the free run of the carriage in a letter spacing direction during which characters are not being written.

It will be seen that I have thus provided a very simple yet highly effective and reliable means for preventing unnecessary and unwarranted longitudinal feed of the ribbon. In the present instance, a free movement of the carriage in a letter spacing direction is afforded by operating either the carriage release or the tabulator key, but the release of the carriage is ultimately effected by an actuation of the same part of the mechanism regardless of whether such release is caused by an operation of the carriage release key or by an operation of the tabulator key. I have thus attained a highly desirable result with a very simple mechanism by employing this part of the mechanism which ultimately releases the carriage to control the mechanism for interrupting the feed of the ribbon.

A further important feature of my invention is the simple and reliable means provided for interrupting the feed of the ribbon, which means

operates to merely move the pinion gear 116 out of meshed relation with its driving gear on the spring drum, thereby providing a disconnecting means without materially increasing the number of parts otherwise required in the usual ribbon feeding mechanism.

Various changes may be made in the construction and certain features thereof may be omitted without departing from my invention as it is defined in the accompanying claims.

What I claim as new and desire to secure by Letters Patent is:

1. In a typewriting or like machine, the combination of a carriage, a spring drum therefor, an escapement wheel operatively connected with said carriage, a movable dog rocker, a releasable feed dog pivotally mounted on said dog rocker in cooperative relation with said escapement wheel to normally hold said carriage against movement under the force of said spring drum, a releasing member for pivotally moving said feed dog relative to said dog rocker to a position out of cooperative relation with said escapement wheel, carriage release keys mounted on said carriage, a bail operatively connected with said release keys and extending longitudinally of the carriage for operating said releasing member, ribbon feeding mechanism including a shaft operatively connected with said spring drum, and means operated by said releasing member for moving said shaft out of operative connection with said spring drum.

2. In a typewriting or like machine, the combination of a carriage, a spring drum therefor, escapement mechanism for the carriage including an escapement wheel, a dog rocker, a feed dog mounted for pivotal movement on said dog rocker into and out of cooperative relation with said escapement wheel, a releasing member cooperative with said feed dog to cause said pivotal movement thereof out of cooperative relation with the escapement wheel, tabulator mechanism, means controlled by said tabulator mechanism for operating said releasing member,

ribbon feeding mechanism including a shaft operatively connected with said spring drum, and means operated by said releasing member for moving said shaft out of cooperative connection with said spring drum.

3. In a typewriting or like machine, the combination of a carriage, escapement mechanism for the carriage including an escapement wheel and pivoted dog rocker cooperative therewith, a feed dog pivotally mounted on said dog rocker for movement therewith into and out of cooperative relation with said escapement wheel, a pivoted releasing member operative to cause a pivotal movement of said feed dog relative to said dog rocker to a position releasing said escapement wheel, carriage releasing means mounted on the carriage and operative to actuate said releasing member, key controlled tabulator stops, a pivoted controlling member operative by each of said tabulator stops to actuate said releasing member, ribbon feeding mechanism actuated by movement of the carriage, and means operated by said releasing member for rendering said ribbon feeding mechanism inoperative.

4. In a typewriting or like machine the combination of a carriage, a spring drum therefor, escapement mechanism for the carriage, carriage releasing means, tabulator mechanism, a releasing member operative by said carriage releasing means and by said tabulator mechanism to free said carriage from control by said escapement mechanism, ribbon feeding mechanism including a shaft disposed substantially parallel with the axis of said spring drum, a gear on said spring drum, a gear on said shaft normally meshing with said gear on the spring drum, a fixed bearing for said shaft spaced from said gear thereon, and means operated by said releasing member for moving said shaft transversely of its length and substantially about said fixed bearing to disengage said gear on the shaft from said gear on the spring drum.

RUSSELL G. THOMPSON.
